UNITED STATES PATENT OFFICE.

THOMAS K. KEITH AND ROSWELL CARLETON, OF HAVERHILL, MASS.

FIRE-ESCAPE.

SPECIFICATION forming part of Letters Patent No. 288,447, dated November 13, 1883.

Application filed February 28, 1883. (No model.)

To all whom it may concern:

Be it known that we, THOMAS K. KEITH and ROSWELL CARLETON, of Haverhill, in the county of Essex and State of Massachusetts, have invented certain Improvements in Fire-Escapes, of which the following is a specification.

This invention has for its object to provide a simple and efficient portable fire-escape adapted to be carried conveniently in a trunk or valise and to constitute a safe means for lowering a person from a building to a point of safety.

To these ends our invention consists in the improved fire-escape which we will now proceed to describe and claim.

Figure 1 is a side elevation. Fig. 2 is a longitudinal section. Fig. 3 is a side view, showing the device in operation.

15 The same letters of reference indicate the same parts in all the figures.

Our improved fire-escape is composed, generally speaking, of a reel, *a*, journaled on an arbor, *b*, a strap or cord, *c*, of any suitable material and length, wound upon said reel, and adapted to be attached at its outer end to a fixed object at the point from which the descent is to be made, a supporting-frame, *d*, supporting the arbor *b*, a device whereby the 25 human body may be suspended from said frame, and suitable means for regulating the rapidity of the rotation of the reel, so that the cord or strap will unwind at a sufficiently slow rate to admit of the safe descent of the person suspended from the frame.

30 The device for suspending the body from the frame consists, preferably, of a strap, *e*, adapted to pass around the body under the arms, as shown in Fig. 1, and provided with hooks or other means for the attachment of its ends to the frame *d*.

The means for regulating the rotation of the reel are preferably those shown in the drawings—viz., a cam-lever, *f*, pivoted at one end 45 of the arbor *b*, and adapted, when swung downwardly on its pivot, to press the sides of the frame *d* inwardly, and plates *g g*, attached to the inner sides of the frame and bearing against washers *i i*, of rubber or other yielding material, interposed between the plates *g g* and the sides of the reel. The arbor is provided at one

end with a head or nut, *k*, bearing against one side of the frame *d*, the cam-lever *f* bearing against the opposite side. The arbor *b* passes loosely through the side of the frame, against which the cam-lever bears. It will be seen, therefore, that a person suspended from the frame *d* can, by moving the lever *f*, exert any desired degree of inward pressure against the sides of the reel and cause the same to rotate 60 as rapidly or as slowly as may be desired; or the lever *f* may be set in any desired position before the descent is commenced.

The strap *c* is preferably composed of stout flat webbing, so that it can be rolled into compact form. Metal tape, wire rope, or any other suitable material may be employed, if preferred.

The upper part of the frame *d* is preferably provided with a cross-bar, *n*, against which the 70 strap *c* bears when the reel is descending. Said cross-bar, by its friction on the strap, assists in retarding the descent of the reel and its load.

When a person desires to use our improved fire-escape, he secures the upper end of the 75 strap *c* to any convenient object in or upon the building, passes the strap *c* around his body and secures it to the frame *d*, and then throws his weight upon said frame. The reel is caused to rotate by the strain thus exerted on the strap, 80 and therefore descends with the frame *d* and its load at a rate depending on the rapidity of rotation of the reel.

We claim—

The improved fire-escape herein described, 85 consisting, essentially, of the open frame having flexible sides, the reel, elastic plates interposed between the reel and frame, the bolt forming the axis of the sheave, the cam-lever pivoted to said bolt and bearing on the frame, 90 and the cord or web and attaching devices, all combined and arranged substantially as shown and described.

In testimony whereof we have signed our names to this specification, in the presence of 95 two subscribing witnesses, this 26th day of February, 1883.

THOMAS K. KEITH.
ROSWELL CARLETON.
